Primary Examiner — Janice Seeger(74) *Attorney, Agent, or Firm* — Montgomery Patent & Design, LLC; Robert C. Montgomery; Joseph T. Yaksich(57) **CLAIM**

The ornamental design for a bunk bed privacy sheet, as shown and described.

DESCRIPTION

FIG. 1 is a perspective side view of a bunk bed privacy sheet depicted in an in-use state with a bunk bed, showing my new design;

FIG. 2 is a perspective side view of the bunk bed privacy sheet depicted in an in-use state in accordance with FIG. 1;

FIG. 3 is a front view thereof with a rear view being a mirror image;

FIG. 4 is a left side view thereof with a right side being a mirror image; and,

FIG. 5 is a top view thereof with a bottom view being a mirror image.

The broken line showing of a bunk bed shown in FIG. 1 is for the purpose of illustrating environment and forms no part of the claimed design.
